FRAMING DEVICE FOR MOTION PICTURE MACHINES

Original Filed March 24, 1920 2 Sheets-Sheet 2

Fig. 5.

UNITED STATES PATENT OFFICE.

MORRIS M. GRUBER, OF BROOKLYN, NEW YORK, ASSIGNOR TO THE BURWOOD CORPORATION, OF SCRANTON, PENNSYLVANIA, A CORPORATION OF NEW YORK.

FRAMING DEVICE FOR MOTION-PICTURE MACHINES.

Application filed March 24, 1926, Serial No. 368,245. Renewed May 5, 1925.

To all whom it may concern:

Be it known that I, MORRIS M. GRUBER, a citizen of the United States, residing at Brooklyn, in the county of Kings and State 6 of New York, have invented certain new and useful Improvements in Framing Devices for Motion-Picture Machines, of which the following is a specification.

This invention relates to a combined in-10 termittent motion and framing device for use in motion picture apparatus, the present application being a continuation in part of my prior application Ser. No. 287,850, filed April 5, 1919.

15 One of the objects of the invention is to provide an intermittent motion mechanism in an exceedingly simple and compact form; with a minimum number of operating parts; and with a rigidity and inflexibility of struc-20 ture that effectually prevents vibration in operation.

Another object of the invention is to so mount the intermittent motion mechanism in the framework of the apparatus that 25 it can be bodily rotated in its seat to thereby directly vary the distance between the eccentrically carried intermittently driven sprocket with relation to the aperture with which the film is to be framed, and that the 30 intermittent motion mechanism can be bodily removed as a single unit from its seat in the framework of the apparatus.

In the construction of my improved inter-35 mittent motion mechanism, I have made use of a simple adaptation of a Geneva stop de-40 vice, this being the most practical construction for the purpose because of the gradual acceleration and retardation of movement produced in the film, so that the film starts 45 slowly into motion, moves rapidly through the middle part of its movement, and gradually loses speed until it comes to a stop, this mode of operation resulting in a de-50 sirable freedom from jerking of the film. I 45 have succeeded in reducing the number of 55 moving parts in my intermittent motion mechanism to two, which is the smallest pos-60 sible number with a Geneva stop construc-65 tion. One of the two moving parts referred 70 to is a driving shaft which directly meshes 75 with the main vertical drive shaft of the 80 machine, carrying at one end a fly wheel and 85 near the other the pin and cam wheel of the 90 Geneva stop device. The other moving part 95 55 is a second shaft carrying at one end the 100

Geneva star wheel and at the other the inter-mittently driven toothed sprocket which gives motion to the film.

The arrangement of the operating parts referred to is such that an exceedingly effec-60 tive condition of balance of the mechanism is obtained. This is brought about by mounting the two operating shafts referred to in oppositely projecting positions in a unitary framework or casing of rigid con-65 struction and which is formed substantially midway between its ends into a circularly-grooved seating member of relatively large diameter having rotatable engagement with the edge of a recess provided for the pur-70 pose in a vertical web member forming part of the framework of the machine. The Geneva drive shaft referred to projects laterally to one side of the seating member and supporting web for engagement with the 75 main drive shaft while the intermittent sprocket is supported on the star wheel shaft at substantially the same distance from the web on the other side of the web, thereby se-80 curing a balanced relation between the 85 points where power is applied to the inter-mittent motion mechanism and where pow-er is applied, in turn, by the intermittent motion mechanism to move the strip of film.

In order to produce a framing operation 85 with the described structure, it is necessary merely to rotate the intermittent motion mechanism framework bodily in its seat in the web recess, whereupon the framework will be rotated about the pin wheel and drive 90 shaft as a center, this shaft being mounted coincidentally with the axis of the frame-work, and the star wheel, and intermittent sprocket wheel shaft which is eccentrically inounted with relation to the framework will 95 be moved in a translating or orbital move-100 ment about the axis of the framework and the pin wheel shaft. This movement of the intermittent sprocket is arranged to vary the distance between the sprocket and the open-ing in the aperture plate with relation to which the film is framed.

Other features of the invention will be hereafter described.

In the drawing:

Fig. 1 is a vertical sectional view of a motion picture projecting machine which includes an embodiment of the invention.

Fig. 2 is a similar view taken from the left of Fig. 1.

Fig. 3 is a similar view taken from the left of Fig. 2.

Fig. 4 is a perspective view showing in detail the means for holding the intermittent motion mechanism in its seat.

Fig. 5 is a vertical sectional view of the intermittent motion mechanism.

Fig. 6 is a horizontal sectional view of the intermittent motion mechanism taken on a line 6—6 of Fig. 5.

Fig. 7 is a view taken from the left of Fig. 6 and partly broken away.

Referring to the drawing, Figs. 1, 2 and 3, the framework of the casing 1 of a motion picture projecting machine is shown, on which may be mounted the upper film reel 2, from which the film 3 may be led by way of upper feed sprocket 4, the film gate 5, intermittent motion mechanism 6 and lower feed sprocket 7 to a suitable take-off reel beneath the projector. The intermittent motion mechanism 6 will form the subject matter of this case.

The device 6 consists of a combined intermittent motion and framing device and comprises two main operating parts, a drive shaft 8 and a driven shaft 9 arranged in a parallel relation but projecting in opposite directions from a supporting framework or casing 10. The drive shaft 8 has a rigid bearing support throughout practically its entire length and at a cut-out portion in the framework 10 has a direct spiral gear connection 11 with the main vertical drive shaft 12 of the machine. The shaft 8 carries at one end the fly wheel 13 and has a cam and pin wheel 14 of a Geneva stop mechanism mounted thereon near the other end. The extreme end of the shaft 8, remote from the end carrying the fly wheel, is provided with a ball thrust bearing 15 to relieve the friction of the thrust exerted in the shaft by the action of the spiral gear connection 11.

Mounted with one end adjacent the pin wheel 14 the driven shaft 9 extends in the opposite direction from that taken by the drive shaft 8. Near the mid portion of the framework is a chamber 16 arranged to hold oil. The shaft 9 is provided with a Geneva star wheel 17 which operatively engages the pin wheel 14 carried by the drive shaft 8. The shaft 9 passes through an elongated bearing member 18 and carries at the other end the intermittently driven film-engaging sprocket 19.

By this construction, I provide a compact, simple and vibrationless structure largely by reason of the condition of balance that is obtained by applying the power of the main drive shaft 12 at one side of the central portion of the device and causing the film-driving sprocket to engage the film at a point on the opposite side of the central portion.

Another feature of the device which aids

in the elimination of vibration resides in the construction of the framework 10 in which the mechanism described is mounted. It will be seen that the framework 10 is of a substantial and rigid character and that not only are massive bearing members of the greatest supporting length for the shafts 8 and 9 provided, but the framework is itself expanded at its central portion into a grooved seating member 20 of substantial diameter. The seating member 20 has a grooved circular periphery formed by the flanges 21 to provide for seating the framework in a recess formed for the purpose in the central web or partition 22 of the machine framework. This seating recess is open to the rear of the machine so that when an anchoring plate 23 carrying a follower 24, and which is held in place with suitable screws 25, is detached the entire intermittent motion mechanism can be removed from the recess and from its place in the machine without disturbing any other operating part. Normally a screw member 26 passing through the plate 23 and follower 24 frictionally engages the periphery of the grooved member 20 and prevents the framework 10 from turning on its seat. A lock nut 27 is provided for holding the screw 26 in locking position. It will be seen that the large diameter of the cooperating seating members will be very effective in preventing vertical vibration of the laterally extending shafts 8 and 9 and that the smoothness and quietness of operation of the mechanism will be correspondingly increased.

Not only does the seating arrangement of the intermittent motion mechanism provide a rigid and vibrationless mounting for the intermittent motion device, but it also provides a very effective framing structure. To produce a framing operation by which the picture sections of the film are placed in register with the aperture in the film gate, it is necessary merely to relieve the pressure of the screw member 26 on the grooved periphery 20 of the framework 10 and to move the hand lever 28 when the framework 10 will be bodily rotated in its seat through the connection formed by the link 29. This will move the star wheel 17 along the periphery of the cam of the cam wheel 14; that is, the star wheel shaft 9 will be given an orbital movement about the shaft 8 as a center. By reference to Fig. 7, it will be seen that the upward or downward movement of the star wheel 17 caused by the slight rotation of the framework 10 will either increase or diminish the distance between the aperture in the film gate and the sprocket 19 at the other end of the star wheel shaft and thereby produce a framing movement. The variation in distance caused by the upward or downward movement of the star wheel 17 will be somewhat increased

by the slight turning movement of the star wheel which is produced as the star wheel follows the circular contour of the cam wheel 14.

- 5 The cut out portion 30 in the framework 10 provides for the rotation of the framework bodily about the shaft 8 without rotating the shaft or striking the vertical drive shaft 12. A limiting cut out portion 31 10 on one of the flanges may cooperate with a suitable pin or lug on the web member 22 to prevent excessive rotation of the framing structure in either direction.

What I claim is:

- 15 1. In a motion picture machine having a vertical web provided with a recess opening to an edge of said web, an intermittent motion device, and a casing for said intermittent motion device, said casing having intermediate its ends a tongue and groove connection with the recess in said web, whereby when the casing is fitted laterally into the recess from the edge of the web the tongue and groove connection will lock 20 said casing against vibration.

2. In a motion picture machine having a vertical web provided with a recess opening to an edge of said web, an intermittent motion device, and a casing for said intermittent motion device, said casing having a transverse groove intermediate its ends, said groove fitting the recess in said web, whereby when the casing is fitted laterally into said recess the engagement of the web with the groove 30 will lock the casing against movement.

3. In a motion picture machine having a vertical web provided with a recess opening to a lateral edge of said web, an intermittent motion device, a casing for said intermittent motion device having a circumscribing groove intermediate its ends formed by flanges integral with the casing, said groove being arranged to receive the edges of said recess when the casing is pressed laterally into the recess from the edge of the web, the interengagement of said groove and the edges of the recess serving to prevent vibration of the casing in the recess.

4. In a motion picture machine having a vertical web provided with a recess opening to a lateral edge thereof, an intermittent motion device, a casing for said device having a circular circumferential groove intermediate its ends formed by flanges integral with said casing, said groove being arranged to receive the edges of said recess when the casing is pressed laterally into the recess from the edge of the web, and the inner end of said recess being semi-circular in formation to provide for the rotation of said casing in its seat and effect a framing action on the film strip.

5. In a motion picture machine having a vertical web provided with a recess opening to a lateral edge thereof, an intermittent

motion device, a casing for said device having a circular circumferential groove intermediate its ends, said groove being arranged to receive the edges of said recess when the casing is pressed laterally into the recess from the edge of the web, a follower formed to fit the outer end of said recess and enter said groove, the inner edges of said recess and said follower providing a circular formation, whereby the casing may be rotated in its seat to effect a framing action on the film strip, said follower being removable to provide for the removal of said casing from said recess.

6. In a motion picture machine having a vertical web provided with a recess opening to a lateral edge thereof, an intermittent motion device, a casing for said device having a circular circumferential groove intermediate its ends, said groove being arranged to receive the edges of said recess when the casing is pressed laterally into the recess from the edge of the web a follower formed to fit the outer end of said recess and enter said groove, the inner edges of said recess and said follower providing a circular seat in which the casing may be rotated to frame the film, means for rotating the casing, and means under the control of the operator for normally holding the casing against vibration.

7. In a motion picture machine having a vertical web provided with a recess opening to a lateral edge thereof, an intermittent motion device, a casing for said intermittent motion device having a cylindrical section provided with a circumferential groove intermediate its ends, said groove being arranged to receive the edges of said recess when the casing is pressed laterally into the recess from the edge of the web, a follower formed to fit the outer end of said recess and form with the inner end of the recess a circular seat for said groove, a driving shaft for said intermittent motion device concentrically journaled in said casing and projecting from one end of said casing, an intermittently driven shaft eccentrically journaled in said casing and projecting from the opposite end of said casing, and a film engaging sprocket carried by said driven shaft, whereby the rotation of the casing in its seat will produce a translating movement of said sprocket to frame the film.

8. In a motion picture machine having a vertical web provided with a recess opening to a lateral edge thereof, an intermittent motion device, a casing for said intermittent motion device having a cylindrical section provided with a circumferential groove intermediate its ends, said groove being arranged to receive the edges of the recess when the casing is pressed laterally into the recess from the edge of the web, a driving shaft for said intermittent motion de-

vice concentrically journaled in said casing, a fly wheel carried by the outer end of said shaft, a Geneva driving wheel carried by the inner end of said shaft, a driven shaft eccentrically journaled in the other end of said casing, a film engaging sprocket carried by the outer end of the driven shaft, a Geneva star wheel carried by the inner end of said shaft for cooperation with said Geneva driving wheel, an oil chamber in 10 said casing in which said Geneva wheel members operate, said casing being rotatable in said recess to move the film engaging sprocket and frame the film.

Signed at Brooklyn in the county of Kings 15 and State of New York, this 17th day of March, 1920.

MORRIS M. GRUBER.
